UNITED STATES PATENT OFFICE

162,019

DISPLAY BOX FOR CRAYONS AND THE LIKE

Joseph C. Foster, Leominster, Mass., assignor to Foster Grant Co., Inc., Leominster, Mass., a corporation of Massachusetts

Application July 29, 1949, Serial No. 4,197

Term of patent 14 years

(Cl. 58—12.6)

To all whom it may concern:

Be it known that I, Joseph C. Foster, a citizen of the United States, residing at Leominster, Worcester county, and State of Massachusetts, have invented a new, original, and ornamental Design for a Display Box for Crayons and the Like, of which the following is a specification, reference being had to the accompanying drawings, forming part thereof, in which:

Figure 1 is a front plan view of a display box for crayons and the like embodying the design;

Fig. 2 is a side elevation of the box;

Fig. 3 is an end elevation thereof;

Fig. 4 is a rear plan view;

Fig. 5 is a vertical section on the line 5—5 of Fig. 1; and,

Fig. 6 is a face view of the filler.

The dominant features of the design reside in the portions of the device shown in full lines.

I claim:

The ornamental design for a display box for crayons and the like, substantially as shown and described.

JOSEPH C. FOSTER.
